UNITED STATES PATENT OFFICE.

GEORGE A. JOHNSON, OF CHICAGO, ILLINOIS, ASSIGNOR TO WILLIAM H. MINER, OF CHAZY, NEW YORK.

FRICITION-GEAR FOR RAILWAY DRAFT-RIGGING.

1,300,404.

Specification of Letters Patent. Patented Apr. 15, 1919.

Application filed February 16, 1918. Serial No. 217,519.

To all whom it may concern:

Be it known that I, GEORGE A. JOHNSON, a citizen of the United States, residing at Chicago, in the county of Cook and State 5 of Illinois, have invented a certain new and useful Improvement in Friction-Gears for Railway Draft-Rigging, of which the following is a full, clear, concise, and exact description, reference being had to the accompanying drawings, forming a part of this specification.

This invention relates to improvements in friction gears for railway draft riggings.

As is well known, in the operation of railway cars, the buffing shocks are generally much heavier than the shocks under draft, which the draft gears are required to absorb. This fact has made it desirable to provide shock absorbing mechanisms of 20 higher capacity under buff than under draft in order that the heavy buffing shocks may be completely absorbed, and at the same time permit an easier action under draft to facilitate starting of the cars.

One object of my invention is to provide 25 a novel arrangement of shock absorbing mechanism which will have substantially double the shock absorbing capacity under buff that it has under draft.

Another and more specific object of the invention is to provide a shock absorbing mechanism, preferably of the friction type, so arranged that two shock absorbing units are arranged in tandem so as to be operable 30 simultaneously and cumulatively in buff, and wherein only the rear of the tandem arranged units is operated under draft.

Still another object of the invention is to provide a shock absorbing mechanism that 40 will have substantially double the travel in buff that it has in draft.

In the drawing forming a part of this specification, Figure 1 is a vertical, longitudinal section of a portion of a draft rigging 45 showing my improvements in connection therewith. Fig. 2 is a horizontal, sectional view of the structure illustrated in Fig. 1 and showing the position of the parts under full buff. Fig. 3 is a vertical, transverse, 50 sectional view, taken substantially on the line 3-3 of Fig. 1. Fig. 4 is a detail, sectional view corresponding to Fig. 1, illustrating the front portion only of the draft rigging embodying another form of my in-

vention. And Fig. 5 is a view similar to Fig. 1, illustrating a further embodiment of 55 my invention.

In said drawing, 10-10 denote channel center or draft sills of a railway car between which, at the rear end of the gear, is 60 secured a transversely extending abutment block 11 forming the rear stop for the draft gear. The draw bar 12 is operatively connected, by a horizontal yoke 13 and coupler-key 14 extending through suitable slots provided in the draw bar yoke and draft sills. Said yoke 13 normally bears against the abutment block 11 and co-operates with a suitably notched rear follower 15, the rear 70 end of the yoke and the follower 15 thereby being supported by brackets 16-16 secured to the inner faces of the draft sills, as clearly shown in Figs. 1 and 2.

The improved shock absorbing mechanism, as shown, comprises two friction units oppositely arranged. These friction units have a common casting A of substantially cylindrical form throughout, said casting A having a friction shell 17 at each end thereof and a central partition or wall 18 dividing the casting A into two substantially identical halves. Co-operable with each friction shell 17 is a circularly arranged series of friction shoes 19 and wedge 20, there being anti-friction rollers interposed between the wedge and the shoes, as indicated at 21 in Fig. 1. Within each chamber of the casting A is placed a heavy main spring 22, each of said main springs bearing at one end 80 against the central partition 18 and at its opposite end against the inner edges of the corresponding set of friction shoes. A long retaining bolt 23 is employed extending from one wedge to the other wedge through 85 the springs and suitable perforations in the spring washers and partition 18. The casting A with the parts contained therein is supported by a detachable saddle plate 24.

At the front of the gear, upper and lower 100 horizontally extending stops are provided in the form of two transversely extending removable keys 25 and 26, respectively. A front follower 27 is interposed between the butt of the draw bar 12 and the front wedge 105 block 20, said follower 27 being slidably supported and guided by and between said stop keys 25 and 26. The rear end of the

draw bar butt is similarly supported and guided, as will be apparent from an inspection of Fig. 1.

The operation is as follows: In buffing, 5 the draw bar will force the front follower 27 rearwardly, thus actuating the front set of friction elements and at the same time forcing the double-ended friction shell rearwardly. This in turn will cause the actuation 10 of the rear set of friction elements and the action will be continued until the full buffing movement is completed, as illustrated by the position of the parts in Fig. 2. It is 15 evident that during this movement, the total permissible travel of the draw bar will equal the sum of the permissible action of each friction unit, which in actual practice will approximate a total travel of three inches. Under draft, it is evident that the casting A 20 will be held stationary against the front stops 25 and 26 so that the front friction unit will be inactive and the shock will be absorbed entirely by the rear friction mechanism and until the rear follower 15 engages 25 with the rear end of the casting A. The draft capacity is therefore one-half of the buffing capacity and the travel of the draw bar is also limited to one-half of the permissible travel under buff.

30 In the form shown in Fig. 4, the arrangement of double-ended friction mechanism is the same as that shown in Fig. 1 and substantially the entire difference resides in the front follower 127 which is provided 35 with upper and lower flanges 227-227 to overlap the rear end of the draw bar 112. The follower construction 127 is employed in those cases where the draw bar butt is of small size or where the spacing between the 40 front upper and lower stops is greater than the vertical height of the draw bar butt, it being evident that a follower of the form shown in Fig. 4 will properly center the draw bar butt in line with the center line of 45 the gear.

In the construction illustrated in Fig. 5,

the double-ended friction mechanism A' is of a type having a considerably higher capacity than the type illustrated in Fig. 1. In Fig. 5, the friction shells 117 proper are 50 substantially cylindrical and the spring casings 200 are of substantially rectangular form open at the top and bottom to permit the use of twin arranged main springs 222 with each set of friction elements. The formation 55 of the casting shown in Fig. 5 is such as to provide upper and lower shoulders 201-201 adapted to coöperate with transversely extending keys forming front stops 225 and 226. The location of the stop keys 60 225 and 226 in the manner shown necessitates the use of additional transverse keys 325 and 326 to support and guide the butt of the draw bar. The operation of the gear is the same as that above described in connection 65 with Fig. 1 and need not here be detailed.

I claim:

1. In a draft rigging, the combination 70 with draft sills, draw bar, and yoke-acting means, of a friction gear shell, means for holding said shell stationary under draft but permitting said shell to move under buff, a set of friction elements coöperable with said shell at its rear end under both buff and 75 draft, and additional shock absorbing means at the front end of the gear and operable under buff only.

2. In a draft rigging, the combination 80 with draft sills, draw bar, and yoke, of a double-ended friction shell having a set of friction elements coöperable therewith at each end, rear and front stop members, said shell being held stationary under draft but movable in buff, both sets of friction elements being operable in buff and only the rear set in draft.

In witness that I claim the foregoing I have hereunto subscribed my name this 7th day of Feb., 1918.

GEORGE A. JOHNSON.
